Primary Examiner — Kevin K. Rudzinski(74) *Attorney, Agent, or Firm* — Curtis L. Harrington; Harrington & Harrington(57) **CLAIM**

The ornamental design for a disc brake caliper bracket, as shown and described.

DESCRIPTION

FIG. 1 is a top and front perspective view of the disc brake caliper bracket, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom plan view thereof; and,

FIG. 7 is a top plan view thereof.

The broken lines illustrate portions of the disc brake caliper bracket that form no part of the claimed design.
